DESIGN FOR A BATHTUB

Bert O. Tilden, Trenton, N. J.

Application May 18, 1934, Serial No. 51,833

Term of patent 14 years

To whom it may concern:

Be it known that I, BERT O. TILDEN, a citizen of the United States, residing at Trenton, in the county of Mercer, State of New Jersey, have invented a new, original, and ornamental Design for a Bathtub, of which the following is a specification, reference being had to the accompanying figure of the drawing forming part thereof.

The figure is a perspective view of a bathtub, showing my new design.

I claim:

The ornamental design for a bathtub as shown.

BERT O. TILDEN.
